UNITED STATES PATENT OFFICE

2,106,646

CHILD'S GARMENT

William Murphey, Chattanooga, Tenn.

Application June 10, 1936, Serial No. 84,543

1 Claim. (Cl. 2-83)

The object of my invention is to provide a novel seat construction for boys', girls' and children's sleeping garments, boys', girls' and children's union suits and waist suits, and to provide on 5 such garments a flap which fastens on the front of the garments and are adjustably buttoned to allow the garments to grow longer as the child grows taller. I attain these and other objects of my invention by the garments illustrated in the 10 accompanying drawings, in which—

Figure 1 is a front plan view of the garment, a portion being broken away to show a detail of a concealed part of the garment;

Fig. 2 is a front plan view of a portion of the 15 garment;

Fig. 3 is a diagrammatic horizontal section on line 3—3 of Fig. 1;

Fig. 4 is a rear plan view of the garment;

Fig. 5 is a diagrammatic vertical section on 20 line 5—5 of Fig. 4; and

Fig. 6 is a side elevation of one of the feet.

Like numerals designate like parts in each of the several views.

Referring to the accompanying drawings; the 25 body 1 of the garment is provided with the facing 2 having buttonholes 3. The overlapped edge portion of the garment is provided with a suitable binding or edging 4. This portion of the garment also carries the buttons 5 which engage in the 30 buttonholes 3. The back of the garment is designated 6, the arms 7 and 8 designate the stitching fastening the sleeve to the body, and 9 a line 35 of stitching finishing the sleeve edge or cuff. The garment has legs 10 with feet 11 and soles 12 which are stitched to the feet 11 by the line of stitching 13.

The rear of the garment is provided with a back flap body 14 having its upper edge and its side edges stitched to the back 6 of the garment 40 by the line of stitching 15 which is disposed as shown in Fig. 4 of the drawings. At the point 13a the member 14 is free from the body of the garment and terminates in a tapered extension depending freely toward the crotch and stitched 45 at 16 to the convex base of the triangular flap 17. The apical portion 18 of flap 17 to which the tapered extension is stitched at 16a extends around the crotch of the garment up the front of the garment, as shown in one of the drawings. 50 The convexly curved line of stitching 16a at the

base of the triangular extension flap gives the desired extra fullness to the back flap of the body, as shown in Fig. 5 of the drawings. Flap 18 has a plurality of buttonholes 20 by which it may be adjustably buttoned at the front of the garment. 5 On the underside of the flap tongue 18 I provide a tape or binding 19 sewed on to the inner surface of the tongue and of sufficient length to extend just beyond each of the buttonholes 20 in the tongue. Each of the legs of the garment is 10 formed of a single strip of material brought together and sewed by the line of stitching 21 which extends from the sole to and across the crotch of the garment. Adjacent the waist of the garment under the upper portion of the back 15 flap body 14 is a cut-out portion 23, as indicated by dotted lines in Fig. 4. The back flap body 14 and also the seat of the garment adjacent the cut-out portion 23 is provided with extra fullness 20 so as to bulge out and leave a larger opening than is apparent from the dotted lines of this opening shown in the drawings. It should also be noted that the seat of the garment is provided with such a fullness as to cause it to go outwardly, as shown diagrammatically in Fig. 5. 25 The flap 17 and tongue 18 are so constructed that the tongue measurement from shoulder to crotch may be lengthened about two and one-half inches. This will allow the garment to be worn longer as the child grows in length. 30

What I claim is:—

A garment of the type described having a cut out portion adjacent the waist in the rear of the garment, and a back flap body having its upper edge secured to the garment above said opening, 35 said back flap body having its side edges secured to the side portions of the body of the garment, and having a tapered extension depending freely toward the crotch, a triangular flap having a convex base, the said convex base being stitched to the bottom edge of the aforesaid tapered extension so as to provide considerable extra fullness in the lower portion of the back flap body, said 40 triangular flap extending around the crotch of the garment and having its apex adjustably fastened to the front of the garment, whereby the length of the body of the garment may be adjusted as the wearer increases in height. 45

WILLIAM MURPHEY. 50
